PORTABLE SANDING MACHINE

John P. Bruck, Toledo, Ohio, assignor to American-Lincoln Corporation, Toledo, Ohio, a corporation of Ohio

Filed Dec. 16, 1958, Ser. No. 53,790

Term of patent 14 years

(Cl. D37—1)

FIG. 1.

FIG. 2.

FIG. 3.

FIG. 4.

FIG. 5.

Fig. 1 is an elevation of one side of the portable sanding machine embodying my new design;

Fig. 2 is a rear end elevational view of the portable sanding machine;

Fig. 3 is a front end elevational view of the portable sanding machine;

Fig. 4 is an opposite side elevational view of the portable sanding machine to that shown in Fig. 1, and

Fig. 5 is a top plan view thereof.

The dominant features of the design reside in those portions shown in solid lines.

I claim:

The ornamental design for a portable sanding machine, substantially as shown and described.
